MIXER BLADE

Robert B. Lurski, Oak Park, Ill., assignor to Club Aluminum Products Company, La Grange Park, Ill., a corporation of Illinois

Filed July 11, 1966, Ser. No. 3,033

Term of patent 14 years

(Cl. D44—1)

FIG. 1 is an elevation view of a mixer blade showing my new design;

FIG. 2 is a bottom plan view thereof;

FIG. 3 is a top plan view thereof;

FIG. 4 is a fragmentary plan view of the mixer blade of FIG. 1 rotated 45° about its longitudinal centerline;

FIG. 5 is a sectional view on the line 5—5 of FIG. 1; and

FIG. 6 is a sectional view on the line 6—6 of FIG. 1. The dashed line showing is for illustrative purposes only.

I claim:

The ornamental design for a mixer blade, substantially as shown and described.
